His Attorney.

UNITED STATES PATENT OFFICE

2,364,961

CONSTRUCTION FOR HEAT-TRANSFER
REDUCTIONClyde Durham, Schenectady, N. Y., assignor to
General Electric Company, a corporation of
New York

Application May 27, 1941, Serial No. 395,415

5 Claims. (Cl. 154—45)

The present invention relates to elastic fluid turbine arrangements and is of particular interest in arrangements including a high pressure turbine and a double-flow, low pressure turbine connected by a cross-over conduit which has a common wall with the exhaust casing of the double-flow turbine. In arrangements of this kind it is important to reduce the heat-transfer from the fluid carried in the cross-over conduit to the fluid contained in the exhaust casing.

The object of the invention is to provide an improved construction and arrangement of this kind whereby the heat-transfer from the cross-over conduit to the fluid contained in the exhaust casing is substantially reduced.

For a consideration of what I believe to be novel and my invention, attention is directed to the following description and the claims appended thereto in connection with the accompanying drawing.

In the drawing, Fig. 1 is a perspective view, partly broken away, of a turbine arrangement embodying my invention; Fig. 2 is a sectional view of the arrangement in Fig. 1; and Fig. 3 is an enlarged detail view of a part of Figs. 1 and 2.

The turbine arrangement shown in the drawing comprises a high pressure turbine 10 and a low pressure, double-flow turbine 11 having an exhaust hood or casing 12 and an inlet 13. Elastic fluid discharged from the high pressure turbine 10 is conducted to the inlet 13 of the low pressure, double-flow turbine 11 by a cross-over conduit or channel 14. The cross-over conduit 14 in the present arrangement is fabricated and has a wall 15 formed by or common with the exhaust hood or casing 12 of the low pressure, double-flow turbine.

A more detailed description of the arrangement so far described is found in the patent to O. Junggren, No. 2,102,416, issued December 14, 1937 and assigned to the same assignee as the present application.

During operation, fluid discharged from the high pressure turbine 10 is conducted by the cross-over conduit 14 to the inlet 13 of the low pressure, double-flow turbine, whence portions of the fluid flow in opposite directions through the two parts of the double-flow turbine and are discharged therefrom into a chamber 16 formed by the exhaust hood or casing 12. As pointed out above, it is important to reduce heat-transfer from the fluid contained in the cross-over conduit 14 through the wall 15 to the exhaust fluid contained in the chamber 16 because such heat-transfer would raise the temperature and pres-

sure of the exhaust fluid and thereby affect the operation and the efficiency of the double-flow turbine.

The heat-transfer is reduced by the provision 5 of lagging which in accordance with my invention is loosely attached to the inner surface of the wall 15. In a preferred embodiment the lagging is formed by a sheet or sheets of metal spaced from and loosely secured to the inner 10 surface of the wall 15 inside the chamber 16. The loose attachment permits relative movement between the lagging and the wall 15 as may occur due to different expansions of the lagging and the wall during operation. An important feature 15 of my invention is the particular construction of the attaching means for the lagging and the method of assembly of the lagging on the wall 15.

The lagging comprises a plurality of overlapping sheets 17 of metal each having a plurality 20 of spaced openings 18. A plurality of pins or supporting and attaching members 19 in the form of flanged cylinders are secured by welds 20 to the common wall 15 of the cross-over conduit and the exhaust hood 12. Each pin has an end 25 portion or flange 21 forming a shoulder 22 for engaging the lagging 17. Another end portion 23 of each cylinder projects loosely through one of the openings 18 of the sheet 17 and is rolled over or expanded or flared to secure the sheet 17 to the cylinder. Preferably a washer 24 is provided between and engages both the expanded end portion 23 and the sheet 17. The openings 18 of the sheet 17 and the end portions 23 of the supporting cylinders form annular clearances 25 to permit relative movement between the wall 15 and the sheet 17.

During assembly, one cylinder 19 is inserted into each opening of the sheet 17 with the shoulder 22 engaging one side of the sheet 17. The washer 24 then is inserted and placed onto the 40 opposite side of the sheet 17. Thereupon the free end portion 23 of the cylinder 19 is conically expanded to engage the washer 24 and to form a snug fit between the lagging sheet and the washer.

45 After assembly of the cylinders on the sheet a unitary lagging unit is formed which thereafter is secured to the exhaust hood by the provision of the welds 20. These welds, as shown in the drawing, are formed between the inner surface 50 of the cylindrical supporting pin and the wall 15.

From another viewpoint, the cylindrical supporting pins, more particularly the end portions or flanges 21 thereof, constitute spacer rings between the lagging sheet 17 and the wall 15. The 55 other portions 23 of the pins may be considered

cylindrical extensions formed on the inner walls of the spacer rings 21 which project through openings in the sheet 17 and have outer ends rolled over or expanded on the side of the sheet 17 opposite the spacer ring 21. The provision of spacer rings with cylindrical extensions projecting through openings of the lagging sheet permit assembly of the spacer rings with the sheet to form a compact unit or a lagging arrangement. The provision of spacer rings facilitates the welding of the lagging arrangements to a wall. The inner diameter of the spacer rings or cylindrical supporting and attaching pins must be large enough relative to their length to permit the insertion of a welding electrode and the formation of the weld 20 between the insides of the spacer ring and the wall 16.

What I claim as new and desire to secure by Letters Patent of the United States is:

1. The combination of a metallic wall, a sheet of lagging having a plurality of openings, and means for supporting the sheet on and spacing it from the wall, said means comprising a plurality of hollow cylindrical supporting pins, a weld fusing the inside of each pin to the wall, each pin having a shoulder engaging the sheet and the outer end of each pin projecting loosely through an opening and being flared.

2. The combination of a metallic wall, a sheet of lagging having a plurality of openings, and means for supporting the sheet on and spacing it from the wall, said means comprising a plurality of hollow cylindrical supporting pins, each pin

5 having a reduced flared outer end portion loosely projecting through an opening of the sheet and having a shoulder engaging the sheet, and a weld formed inside the cylindrical pin and fusing it to the wall.

3. Lagging arrangement comprising a sheet of lagging having a plurality of openings, and means for loosely supporting the sheet when attached to a wall comprising a plurality of cylindrical pins each having a shoulder engaging the sheet and having an end portion loosely projecting through one of the openings and being expanded, and a washer between the expanded portion and the sheet.

4. A housing having a metallic wall, a sheet of lagging having a plurality of openings, and means for spacing the sheet from the wall and supporting it thereon to reduce heat-transfer through the wall, said means comprising a plurality of spacer rings, means loosely connecting the rings to the sheet in alignment with the openings therein, and welds fusing the inside only of each ring to the wall.

5. The combination of a metallic wall, a lagging arrangement supported thereon and including a sheet having a plurality of openings, a hollow cylinder for each opening having a flange disposed between and engaging the wall and one side of the sheet and having a flared end portion adjacent the other side of the sheet, and welds securing the inside of the cylinders to the wall.

CLYDE DURHAM.
